UNITED STATES PATENT OFFICE.

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA.

MIXING APPARATUS.

Application filed August 5, 1921. Serial No. 490,171.

To all whom it may concern:

Be it known that I, FRANK A. BROWNE, a citizen of the United States, residing in Wayne, in the county of Delaware and State of Pennsylvania, have invented certain new and useful Improvements in Mixing Apparatus, whereof the following is a specification, reference being had to the accompanying drawings.

10 My invention relates generally to mixing apparatus and more especially to that type adapted for mixing materials used in the manufacture of so called prepared roofings. In this art, webs usually of felt saturated with a suitable bituminous waterproofing compound are used as bases to which appropriate finishing surfacings are subsequently applied for the purpose of rendering the roofings more durable in use and of securing contrasting or variegated color effects. Such surfacings may be either of plain asphaltum or mixtures of asphaltum and finely divided mineral matter of different sorts such as sand, slate, etc.

25 Amongst the objects of my invention are to enable the operation of mixing surfacing materials such as above noted, to be carried on continuously; and to make it possible to control the relative quantities of the ingredients used so that any desired proportions may be had.

Other objects and attendant advantages of my invention will become readily apparent from the detailed description which follows:

35 In the drawings, Fig. I is a longitudinal sectional view through a mixing apparatus conveniently embodying my invention; and

40 Fig. II is a staggered vertical cross section of the same viewed in the direction of the arrows II-II in Fig. I; and Fig. III is a diagrammatic showing illustrative of the relative disposition of certain agitating elements and end propeller blades hereinafter fully described.

45 The apparatus herein shown as typical of my invention comprises a receptacle 1 which is in the form of a horizontally disposed cylinder having an enveloping jacket 2 for the circulation of a suitable fluid heating medium whereby the contents of the receptacle are maintained in a molten or fluid condition. Extending axially through the receptacle 1 is a shaft 3 which is supported for rotation in bearings 4-4 mounted upon

suitable pedestals or standards 5, 5 at the exterior. At the regions where the extremities of the shaft 3 protrudes through the end walls of the receptacle, I have provided dished baffle disks 6, 6 which serve to prevent escape of the molten material at these regions. Said disks are accommodated within suitable recessions 7-7 of the end walls of the receptacle and are overhung or overlapped by fixed guard plates 8-8.

50 Fixed to the shaft 3 within the receptacle at intervals lengthwise of the same, are agitating elements 10, 10 each consisting of two paddle blades disposed diametrically opposite one another with respect to a central split hub. Alternate pairs of the elements 10 are preferably arranged at right angles, relatively, so that agitation set up by the paddles is rendered the more uniform. The portion of the shaft 3 which lies within the receptacle is square in cross section as best shown in Fig. II of the drawings and the bosses of the agitating elements 10 are correspondingly apertured to fit accurately thereon. Clamp bolts 11, 11 are herein shown as suggestive of means for securing the agitating elements 10 to the shaft. By this construction, the possibility of working loose, or relative displacement of said elements is reduced to a minimum.

55 In addition to the agitating elements 10, I have mounted to the shaft 3 directly adjacent the end walls of the receptacle 1, propellers 12, 12. These propellers 12 are operative in opposition to one another and tend to direct the materials being mixed toward the center of the receptacle to maintain them within the province or field of the intermediate paddles or agitating elements 10, 10 so that thorough agitation and mixing are assured. The propellers 12 are moreover, further functional in directing the material in a direction away from the deflecting disks 6, 6 thereby assisting in preventing escape or leakage through the channels previously pointed out. The shaft 3 may be driven by any suitable means such for example as a sprocket wheel 13 capable of being coordinated, by chain, with any convenient source of power.

60 Molten asphaltum is introduced to the receptacle 1 under sufficient pressure to induce continuous flow, through a fitting 15 which is jacketed as at 16 for a purpose analogous to that already mentioned. Said fitting 15

105

110

has an inclined or gravity flow duct 17 which discharges into the receptacle 1 through an aligned opening in the right hand end wall of the latter. The molten asphaltum is conducted to the mixing apparatus through a jacketed conduit 18 which leads from a suitable source of supply (not shown) and discharges into the duct 17 by way of a branch 19.

10 The material, after mixing, leaves the receptacle through an outlet in the form of a stand pipe 20 which discharges directly into a conduit 21 similar to the conduit 18 above referred to. Said stand pipe 20, it will be 15 noted, is located at the end of the receptacle 1 opposite to that at which the latter is charged so that short circuiting is positively prevented. Said stand pipe 20 also serves to maintain a constant quantity of the material in the receptacle so as to insure thorough mixing under the agitation of the paddles. The receptacle 1 is further provided with a pipe 22 through which it may be completely drained when desired.

20 The fitting 15 is surmounted by a device 25 for introducing to the receptacle any pulverulent or granular material which is to be mixed with the molten bitumen. Said device 25 comprises a hopper 26 whose outlet communicates directly with the duct 17. Horizontally disposed across the outlet of the hopper is a fluted measuring rotor 27 secured to shaft 28. Said shaft 28 is journalled in appropriate bearings in opposite 35 walls of the hopper 26, and has fixed to one of its ends a sprocket wheel 29, which, in practice, is driven by means capable of transmitting motion at different speeds so that rotation of the fluted element 27 may 40 be varied to control the liberation of the pulverulent or granular material in different proportions to the asphaltum flowing through the duct 17. In order to secure better control in measurement of the material, the lower wall or bottom of the 45 hopper 26 is carried well across the outlet beneath the fluted rotor 27 as clearly shown in Fig. II. In cases where needed, a multiplicity of the devices 25 may obviously be employed in introducing as many other different ingredients.

50 While I have described my invention as being advantageously applicable to mixing of materials used in the manufacture of bituminous roofings, it is of course to be understood that it may be employed with equal advantage in other arts.

Having thus described my invention, I claim:

55 1. In a mixing apparatus including a mixing vessel and agitator, a closed, tubular conduit adapted to be connected to a source of fluid ingredient supply, and a lateral

branch formed with the conduit and intersecting the channel of the same through 65 which to introduce powdered ingredients for admixture with the fluid stream, the velocity of the stream creating a partial vacuum in the branch to draw the ingredients into the stream.

70 2. A mixing apparatus comprising a receptacle through which the materials to be mixed are continuously passed; an inlet at one end of the trough through which the materials are introduced to the receptacle; 75 and an outlet at the opposite end of said trough through which the materials are discharged, the mouth of said outlet extending well above the bottom of the receptacle to insure at all times, maintenance of a 80 definite quantity of the materials within the receptacle to insure thorough mixing.

3. In a mixing apparatus including a vessel and agitator, a tubular conduit adapted for connection to a source of fluid 85 ingredient supply, said conduit having a horizontal portion terminating in a downwardly inclined portion entering the vessel, and a vertical branch of said conduit located at the point of flexure through 90 which to introduce powdered ingredients into the fluid stream.

4. An asphalt mixer comprising a receptacle having an inlet means for asphalt and granular material, an agitator within 95 the receptacle, a normal outlet comprising a stand pipe extending into the receptacle to ensure retention of a predetermined quantity of material in the receptacle and to permit constant drainage of mixed material, and an auxiliary outlet means to completely drain the receptacle when desired.

5. In a mixing apparatus of the type described, the combination of dished baffle disks accommodated in complementary recessions about the mixing receptacle journals, and reversely pitched propellers adjoining said journals operative to prevent seepage of material therethrough.

6. In a mixing apparatus of the type described, the combination of dished baffle disks accommodated in complementary recessions concentric with the mixing apparatus journals, overhung guard plates partly closing in said disks, and reversely pitched propellers adjoining said journals operative to force material away therefrom whereby seepage through said journals is prevented.

110 In testimony whereof, I have hereunto signed my name at Philadelphia, Pennsylvania, this fourth day of August, 1921.

FRANK A. BROWNE.
